ASH RECEPTACLE

Roy W. Parkinson, Buffalo, N. Y., assignor to Fred C. Smith, Buffalo, N. Y.

Application November 29, 1939, Serial No. 306,701

4 Claims. (Cl. 220—20.5)

This invention relates to improvements in ash receptacles for smokers and more particularly is concerned with a receptacle of the kind wherein a tray is associated with a receiver in such a manner that the contents of the former may be discharged into the latter by the operation of shutters which normally close the discharge opening through which the tray and receiver communicate.

One object of the invention is to provide a tight seal between the tray and receiver, whereby to prevent the escape of smoke or odors from the receiver.

A further object is to provide a receptacle which is so designed that the shutters are reinforced against the forces of distortion to which they may be subjected when, in extinguishing cigarettes and cigars, the lighted ends thereof are pressed against them and rubbed.

A still further object is a receptacle wherein provision is made for protecting the shutter actuating mechanism from the contents of the receiver.

A still further object is to provide a receptacle which is pleasing and attractive in appearance.

A still further object is to provide a novel design and arrangement of the parts of the receptacle, whereby simplicity and economy in construction are obtained and facility in the operation of the shutters is insured.

Embodiments of the invention are illustrated in the accompanying drawings in which:

Figure 1 is a perspective view of the tray of a receptacle in which the features of the invention are incorporated.

Figure 2 is a section taken along line 2—2 of Figure 1.

Figure 3 is a section taken along line 3—3 of Figure 2, the cover piece 23 being omitted.

Figure 4 is a fragmentary section taken along line 4—4 of Figure 3.

Figure 5 is a section taken along line 5—5 of Figure 2, the cover-piece 23 being shown in its entirety.

Figure 6 is a perspective view of a modification wherein the tray is a permanent part of the receptacle.

Figure 7 is a section taken along line 7—7 of Figure 6.

Figure 8 is a section taken along line 8—8 of Figure 7, the member 53 being omitted.

Figure 9 is a fragmentary section taken along line 9—9 of Figure 7, the member 53 being shown for its full depth.

Figure 10 is a fragmentary section taken along line 10—10 of Figure 9.

Figure 11 is a fragmentary view of another embodiment of the invention.

Figure 12 is a fragmentary section taken along line 12—12 of Figure 11.

Figure 13 is a fragmentary section taken along line 13—13 of Figure 12.

Figure 14 is a fragmentary section taken along line 14—14 of Figure 11.

Figure 15 is a perspective view of another embodiment of the invention.

Figure 16 is a section taken along line 16—16 of Figure 15, the member 99 being omitted.

Figure 17 is a perspective view of the rock member of the shutter actuating mechanism.

Figure 18 is a section taken along line 18—18 of Figure 16.

Figure 19 is a section taken along line 19—19 of the same figure.

The receptacle may be designed for use on a table or desk or, if desired, be incorporated in a floor stand. As illustrated in Figures 1 through 5, it includes a tray 18 and a receiver 19 (Figure 2), the latter being sufficiently indicated for the purpose in view by a showing of the top wall 20 thereof. The tray is formed with a bottom wall 21 and a side wall 22, the said bottom and side walls providing a pan, and it includes a cover-piece 23.

The latter is formed with an annular flange 24 and a conical section 25 which tapers to a neck 26, the said neck delimiting an outlet 27. The flange 24 seats upon the side wall 22 and is secured thereon by nut-and-bolt fastenings 28 (Figure 4), the marginal edge of the flange being down-turned as indicated at 29. The tray fits in an opening 30 in the top wall of the receiver, preferably being removably secured therein by a plurality of angularly inclined projections 31

which are formed upon the side wall 22. The projections pass through enlargements 32 (Figure 5) of the opening 30, whereby upon rotation of the tray, portions of the top wall of the pan are engaged between the projections 31 and the down-turned edge 29 of the cover-piece.

The bottom wall 21 of the pan is formed with a discharge opening 33 which registers with, and which is located directly below, the outlet 27 in the cover-piece. Shutters 34 and 35 are carried

by the bottom wall 21 and are arranged over the discharge opening. They are pivotally mounted upon pins 36 which are carried by the bottom wall, and are normally held closed by springs 37. One end of each of the said springs is connected

55 to the outer end of a rod 38 while the opposite

end is connected to a tail-piece 39 of one of the shutters, the rods 38 being carried by the heads of the pins 36. Preferably the shutters are supported close to, but out of contact with, the neck 26 of the cover-piece. Hence they provide a bottom for the cover-piece without the possibility of the neck of the latter interfering with their operation. The shutters fit closely against the bottom wall of the tray while the springs 37 hold their co-acting edges in tight abutting relation. The discharge opening is, therefore, normally sealed in such a manner that the escape of smoke or odors from the receiver is prevented. The construction described has the further advantage that the shutters, being supported throughout their length, are reinforced against the forces which might bend or otherwise deform them when, in quenching or snuffing cigarettes and cigars, the lighted ends thereof are pressed and rubbed against them.

Means is provided for opening the shutters 34 and 35 against the action of the springs 37, whereby to permit the discharge into the receiver of the ashes, cigarettes and other materials which may have accumulated in the tray. For this purpose the tray carries a ring 40. The latter provides a rim for the tray and is formed with an inner laterally extending flange 41 which seats upon the flange 24 of the cover-piece and with an outer marginal flange 42 which fits over the down-turned edge 29 of the cover-piece. The ring is secured to the cover-piece by posts 43. The latter extend through arcuate slots 44 (Figure 5) which are formed in the flange 24 of the cover-piece and are located in the vicinity of the side wall 22 of the pan, terminating just short of the bottom wall 21; they pass through openings 45 in the top of the ring and screw into diametrically opposed lugs 46 carried by the ring; and they are formed with annular grooves 47 in which portions of the flange which define the slots 44 are located. The mounting of the ring 40 in the manner described enables it to be rotated in a clockwise direction through a predetermined angular distance. The lower ends of the posts 43 are located in slots 48 which are formed in the tail-pieces of the shutters. Hence when the ring 40 is rotated the corresponding movement of the posts 43 is transmitted to the shutters through the agency of the tail-pieces and they are moved, against the action of the springs 37, to the dotted line positions shown in Figure 3. Movement of the ring 40 for the purpose described is facilitated by the lugs 46, the thumb of one hand being placed behind one of them and a finger of the same hand being placed behind the other. A pushing movement of the thumb accompanied by a pulling movement of the finger will thereupon cause the ring to rotate until the shutters are open. Upon release of the lugs 46 the springs 37 return the shutters to their closed positions, the return movement of the tail-pieces of the shutters being transmitted through the posts 43 to the ring 40 to restore the latter to its original position. The lugs 46 may be, and preferably are, formed with depressions 49 in which partially consumed cigarettes or cigars may be rested.

Preferably the slots 44 are enlarged at one end as indicated at 44a (Figure 5). When the parts are being assembled the posts 43 are inserted in the enlarged ends of the slots, are adjusted lengthwise until the portions of the flange 24 which define the narrow portions of the slots 75

are located opposite the grooves 47 and are then moved laterally to cause the said portions to enter the said grooves. The cover-piece is then secured in place by the nut-and-bolt fastenings 28, being first adjusted, however, so that during subsequent manipulations of the ring 40 to operate the shutters in the manner described the posts will be prevented from moving far enough to enter the enlarged ends of the slots. Separation of the ring from the tray is thus prevented.

From the foregoing it will be apparent that the contents of the tray may be discharged with facility, and as desired, into the receiver. The shutters 34 and 35 are supported over the discharge opening and hence any pressure to which they may be subjected incident to the use of the receptacle tends to force them more tightly against the bottom of the pan. The seal which they provide, therefore, will not be impaired. As the shutters are relatively thin it is preferred that they carry stops 50 (Figure 3) which are so located that each engages the tip of the companion shutter, to thereby prevent the shutters, as they close, from moving beyond the positions in which their co-acting edges abut. It will be noted that the actuating mechanism for the shutters is wholly enclosed by the side and bottom walls of the pan and the cover-piece. The said mechanism, therefore, is protected from the contents of the receiver as well as the contents of the tray. Interference with, or impairment of, the operation of the shutters is thus prevented.

35 A modified form of the invention is illustrated in Figures 6 through 10. In this embodiment the tray is built into, and is made a permanent part of, the receiver. The latter is sufficiently indicated by a showing of the top wall 51 and, 40 as in the embodiment described heretofore, the top wall is formed with an opening 52. A member 53 which is arranged in the said opening is adapted to provide the tray, the said member having a marginal flange 54 which seats upon the portion of the top wall surrounding the opening and tapering toward, and terminating in, a neck 55 which defines an outlet 56. A plate 57, arranged under the conical member 53, is formed with a discharge opening 58 which is located under the neck 55 and is secured to the conical member by arms 59, the said member being provided at spaced intervals with tongues 60 (Figures 9 and 10) which are inserted through slots 61 formed in the ends of the arms 59 and bent upwardly against the under side of the top wall of the receiver. The discharge opening 58 is normally closed by shutters 62 (Figure 8). The latter, which also provides a bottom for the conical member 53, are pivotally mounted upon pins 63 which are carried by the plate 57 and are biased toward closed positions by springs 64. One end of each of the springs is connected to a tail-piece 65 of the associated shutter while the opposite end is connected to the associated arm 59.

70 The shutters 62 may be opened by rotating a ring 66 through a predetermined angle in a clockwise direction. To facilitate this the said ring carries diametrically opposed lugs 67 which are similar to, and which are utilized in the same manner as, the lugs illustrated in connection with the embodiment shown in Figure 1. The movement of the ring 66 is transmitted to the shutters by posts 68. The latter screw into threaded

openings in the ring (Figure 7) and have lower ends which are located in slots 69 formed in the tail-pieces of the shutters. In this connection it will be noted that the posts 68 are located beyond the marginal edge of the conical member. The top wall 51 of the receiver, therefore, is cut away as indicated at 70 (Figure 9) to permit travel of the said posts through the necessary range of movement, washers 71 which are carried by the posts engaging the under side of the top wall to secure the ring 66 thereto in such a manner that it may be rotated in the manner and for the purpose described.

In the embodiment of the invention illustrated in Figures 11 through 14 the tray which is indicated at 72 is similar to that shown in the first embodiment in the respects that it includes a pan having a bottom wall 74 and a side wall 75 and a cover-piece 76 and is removably attached to the receiver, the latter being sufficiently illustrated for the purpose in view by a showing of the top wall 73 thereof. The cover-piece is formed with an annular flange 77 which in turn is formed with extensions 78 (Figure 13) which rest upon seats 79 formed by cutting away parts of the side wall 75 and it tapers to a neck 80 which defines an outlet 81, the bottom wall of the pan being formed with a discharge opening 82 which is located under the neck and which is normally closed by shutters 83. The latter are pivotally mounted upon pins 84 carried by the bottom wall 74, are provided with tail-pieces 85 and are held closed by springs 83a which are connected to the tail-pieces.

Discharge of the contents of the tray into the receiver is facilitated by grasping diametrically opposed stems 86. The latter are carried by the flange 77 of the cover-piece. They have lower ends which are located in slots 88a formed in the tail-pieces of the shutters; and they are adapted to be moved in a clockwise direction through a predetermined angular distance in substantially the same manner as the lugs 46 of Figure 1, it being understood that as the cover-piece carries the stems 86 it will be rotated with the latter during operation of the shutters.

The extensions 78 are held upon their seats by an annular ring 87. The latter is formed with an inner flange 88 which seats upon the flange 77 of the cover-piece and with a marginal flange 89 which fits around the upper portion of the side wall of the pan, the marginal flange extending downwardly to close the openings formed in providing the seats 79. The ring is secured in the position described by nut-and-bolt fastenings 90 (Figures 11 and 14), slots 91 being formed in the flange 77 of the cover-piece to provide for its necessary range of travel. Slots 92 which are formed in the ring permit movement of the stems 86 through the necessary range. Preferably closure strips 93 are carried by the stems 86, the latter being formed with enlargements 94 (Figure 12) which hold the strips against the underside of the ring. The strips move with the stems when the latter are manipulated to operate the shutters and are of such a length that they close the slots 92 at all times. In other respects the receptacle is similar to, and the parts thereof function in substantially the same manner as, that shown in Figure 1.

The receptacle illustrated in Figures 15 through 19 includes a tray which is adapted to be removably attached to a suitable receiver, the top wall of the latter being indicated at 95 (Figure 18) and being formed with an opening 96. The

tray comprises a pan having side and bottom walls 97 and 98, respectively, and a cover-piece 99. It fits in the opening 96 and is removably secured therein by angularly inclined lugs 100 which are carried by the side wall of the pan and which engage the under side of the wall 95 of the receiver. The cover-piece, which is secured upon the pan by nut-and-bolt fastenings 101, tapers toward an outlet opening 102. The latter is delimited by a neck 103 which terminates short of the bottom wall of the pan and registers with a discharge opening 104 formed therein. The shutters, indicated at 106, are pivotally mounted upon pins 107 carried by the bottom wall 98 and located at opposite sides of the discharge opening. They are arranged in the space between the neck 103 and the bottom wall and they normally occupy positions in which they close the discharge opening 104 and provide a bottom for the tray.

The shutters are formed or provided with tail-pieces 108 which are substantially parallel and which extend in the same general direction with respect to the pins 107. The tail-pieces have offset ends 109a which are connected by a U-shaped link 109, the laterally extending portions of the link serving to space the connecting bar 110 at one side of the outlet and discharge openings while the offset ends of the tail-pieces space the link above the bottom wall of the pan so that the shutter mounted on the side of the pan adjacent the link can move under the link when it is opened. The link carries an angular extension 111 and is normally held in a position corresponding to the closed position of the shutters by a spring 112 which is connected at one end to the extension. The link may be actuated against the action of the spring to open the shutters by depressing a plunger 113. The latter has a head 114 which extends through an opening 115 formed in the rim of the cover-piece and carries a stem 115a which extends through an opening 116 formed in the bottom wall of the pan, the openings 115 and 116 providing guideways and permitting free vertical movement of the plunger within the desired range. The head of the plunger seats upon an upper outwardly extending arm 117 of a rock member 118, the said member being pivotally mounted upon a supporting bar 119 which is suitably secured at its ends to spaced portions of the side wall of the pan and which is formed with a hook 119a to which one end of the spring 112 is connected. A lower inwardly extending arm 120 which is formed or provided upon the rock member is located behind and abuts the link extension 111.

From the foregoing it will be apparent that when the plunger 113 is depressed the member 118 is rocked upon its pivot to advance the link 109 against the action of the spring 112 to thereby open the shutters and permit discharge of the contents of the tray into the receiver. Upon release of the plunger the spring 112 automatically restores the parts to their normal positions, it being noted that the end of the stem 115a is upset to fix the upper limit of the range of movement of the plunger. The actuating mechanism described has the advantage that it is simple in design, can be made of light metal parts and can be operated with a minimum of effort.

I claim as my invention:

1. A closure for an ash receiver of the character described including a pan having a bottom wall and a side wall, a cover-piece which fits upon said pan and which is adapted to provide a tray,

said cover-piece tapering toward an outlet, said bottom wall having a discharge opening which is located below and in close proximity to said outlet and which registers with said outlet, a pair of shutters located between said tray and bottom wall and pivotally mounted upon said bottom wall to slide thereon, said shutters cooperating to normally close said discharge opening and provide a bottom for said tray, an element which is operable to open said shutters to discharge the contents of said tray through said outlet and opening into said receiver and means located within said pan for connecting said element and said shutters.

2. A closure for an ash receiver of the character described including a pan having a bottom wall, a side wall and a cover-piece which is adapted to provide a tray, said cover-piece tapering toward an outlet, said bottom wall being formed to provide a discharge opening which is located below and in close proximity to said outlet and which registers with said outlet, a pair of shutters located between said tray and bottom wall and pivotally mounted upon said bottom wall to slide thereon, said shutters cooperating to normally close said discharge opening and provide a bottom for said tray, a depressible element for opening said shutters to discharge the contents of said tray through said outlet and opening into said receiver and means located within said pan for transmitting the movement of said element to said shutters.

3. A closure for an ash receiver of the character described including a pan having a bottom wall, a side wall and a cover-piece which is adapted to provide a tray, said cover-piece tapering toward an outlet, said bottom wall being formed with a discharge opening which is located under and in close proximity

- to said outlet and which registers with said outlet, a pair of shutters located between said tray and bottom wall and pivotally mounted upon said bottom wall to slide thereon, said shutters cooperating to normally close said discharge opening and provide a bottom for said tray, a link connecting said shutters, resilient means for normally holding said shutters closed and means including a depressible element for moving said link against the action of said resilient means to open said shutters to discharge the contents of said tray through said outlet and opening into said receiver, said shutters, link and resilient means being located within said pan.
4. A closure for an ash receiver of the character described including a tray having an outlet, a horizontal plate which is located below and in close proximity to said outlet and which is formed with a discharge opening which registers with said outlet, a pair of shutters located between said tray and plate and pivotally mounted upon said plate to slide thereon, said shutters cooperating when closed to provide a bottom for said tray and to close said discharge opening, the pivots for said shutters being located at opposite sides of said discharge opening, each of said shutters having a tail-piece, a link connecting the tail-pieces of said shutters, resilient means for normally holding said shutters closed, a rock member and a plunger which may be depressed to actuate said rock member and thereby move said link to open said shutters against the action of said resilient means to discharge the contents of said tray through said outlet and opening into said receiver, said plate engaging the under sides of the shutters in spaced relation with respect to their pivots to reinforce them against downward deflection.

ROY W. PARKINSON.
